UNITED STATES PATENT OFFICE

ROBERT J. SEATOR, OF BATTLE CREEK, MICHIGAN, ASSIGNOR OF ONE-HALF TO HERBERT MATTHEWS, OF BATTLE CREEK, MICHIGAN

HUMIDIFIER AND AIR CIRCULATOR

Application filed January 22, 1932. Serial No. 588,171.

The main object of my invention is to provide an improved air washer, humidifier and air circulating unit that is particularly useful in connection with the cold air supply of hot air furnaces and the like.

Another object is to provide a device of this character that is simple and economical in construction and economical and efficient in operation.

10 Objects relating to details and economics of my invention will appear from the description to follow. The invention is defined and pointed out in the claims.

15 A structure which is a preferred embodiment of my invention is illustrated in the accompanying drawings, in which:

Fig. 1 is a fragmentary longitudinal vertical section of a device embodying the invention associated with the cold air supply 20 inlet of a hot air furnace, the furnace being shown in dotted lines.

Fig. 2 is an enlarged fragmentary transverse section on a line corresponding to line 2—2 of Fig. 1.

25 Fig. 3 is an enlarged fragmentary detail of the water impeller shown partially in section on a line corresponding to line 3—3 of Fig. 2.

Fig. 4 is an enlarged fragmentary detail 30 of the impeller, a portion thereof being broken away and shown in vertical section.

In the embodiment illustrated in the accompanying drawings 1 represents a hot air furnace having a supply inlet 2. My improved air circulating, washing and humidifying unit designated generally by the numeral 3 is operatively associated with this supply inlet.

40 In the embodiment illustrated the unit consists of a frame 4 provided with legs 6 supporting it in an elevated position above the floor or surface 5. The frame illustrated is formed of angle iron and is of substantially rectangular shape.

45 The driving motor 7 is mounted on a pedestal 8 and provided with a shaft 9 connected to the fan shaft 10 by the flexible connection or shaft coupling 11. The inner end of the fan shaft 10 is supported in a bearing 12 on the pedestal 13 carried by the frame.

The shaft 10 carries the fan 14 and a water impeller or rotor 15 which consists of a cylindrical body having outlet orifices 16 in the periphery thereof so that, when the water is supplied thereto and the impeller rotated, the water is discharged in a spray or curtain across the current of air induced by the fan.

55 At one end the impeller 15 has a central opening 17 to receive the nozzle or discharge end 18 of the pump discharge pipe 20. This pipe has a valve 21 and regulates the amount of water delivered to the impeller. The pump 19 is shown mainly in conventional form.

60 The pump is supported below the water level of the sump pan 24 by means of the hanger 25. This hanger 25 is attached to the gear box 26 which is journaled upon or supported by bearings coaxing with the shaft 10. Thus supported the pump may be 65 swung laterally or rotated around the shaft as a pivot to clear the pan, permitting the ready removal of the pan for cleaning. The hanger is supported in its upright position 70 by means of an arm 27 having a catch portion 28 engaging one of the longitudinal rails of the frame.

75 The pump 19 is provided with a vertical shaft 29 connected to the fan shaft 10 through coaxing worm gears 30 and 31 so that the pump is driven whenever the fan is in operation. A grease cup 32 is provided for supplying the gear box with lubricant and this not only lubricates the gears but 80 also the bearing portions of the gear box.

85 The fan is provided with a casing 33 which constitutes a conduit for the air current induced by the fan, this casing being connected to deliver to the air supply conduit 2 of the furnace. At its outer or front end the casing is provided with an enlarged trough-like portion 35 disposed in the plane of the impeller so that the water discharged by the 90 impeller, not taken up by the passing air, is collected and returned to the sump pan.

95 The unit is provided with a housing 36 to which the air supply conduit 39 is connected.

The motor may be controlled either ther-

mostatically or manually, as desired, the control means not being illustrated.

Instead of using the sump pan and re-circulating the water, the nozzle 18 may be connected to a source of water supply under pressure, the sump water being discharged from the sump as by means of a suitable drain connection.

With the parts thus arranged a spray-like curtain of water is discharged across the current of air induced by the fan and the air is humidified and washed, which renders the apparatus very desirable for household heating systems. In the embodiment illustrated, employing the pump, the water is repeatedly used, so the water cost is nominal. At the same time the water in the sump pan can be replenished or renewed and the pan very conveniently cleaned.

I have illustrated my improvements in an embodiment which I have found highly satisfactory. I have not attempted to illustrate and describe various adaptations and modifications which I contemplate as it is believed that this disclosure will enable those skilled in the art to embody or adapt my improvements as may be desired.

Having thus described my invention what I claim as new and desire to secure by Letters

Patent is:

1. In an apparatus of the class described, the combination of a frame, a water pan, a motor provided with a shaft mounted on said frame, a fan provided with a shaft mounted on said frame and flexibly connected to said motor shaft, a centrifugal water impeller carried by said fan shaft, a hanger journaled to said fan shaft, a water pump supported by said hanger in operative relation to the water within the pan, an arm on said hanger detachably engageable with said frame for holding the pump in operative position and when disengaged permitting the swinging of the pump upwardly to clear the pan, a discharge pipe for said pump delivering to said impeller, and a fan casing mounted on said frame and having a trough-like water receiving portion surrounding said impeller and discharging to said pan.

2. In an apparatus of the class described, the combination of a frame, a water pan, a fan provided with a shaft mounted on said frame, a centrifugal water impeller carried

by said fan shaft, a hanger journaled to said fan shaft, a water pump supported by said hanger in operative relation to the water within the pan, an arm on said hanger detachably engageable with said frame for holding the pump in operative position and when disengaged permitting the swinging of the pump upwardly to clear the pan, and a discharge pipe for said pump delivering to said impeller.

3. In an apparatus of the class described, the combination of a horizontal blower shaft having a centrifugal water impeller thereon, a gear housing journaled to said shaft, a water pump having a vertical shaft geared to said blower shaft in said housing, a vertical pump discharge pipe delivering to said impeller, a hanger carried by said housing and supporting said pump and pipe, a water pan arranged under said pump, and a substantially horizontal latching arm on said hanger for holding the pump in operative position and when disengaged permitting the swinging of the hanger about the blower shaft to clear the water pan.

4. In an apparatus of the class described, the combination of a horizontal blower shaft having a centrifugal water impeller thereon, a gear housing journaled to said shaft, a water pump having a shaft geared to said blower shaft in said housing, a pump discharge pipe delivering to said impeller, a hanger carried by said housing and supporting said pump and pipe, a water pan arranged under said pump, and a latching arm on said hanger for holding the pump in operative position and when disengaged permitting the swinging of the hanger about the blower shaft to clear the water pan.

5. In an apparatus of the class described, the combination of a blower shaft having a centrifugal water impeller thereon, a hanger supported for independent rotation about the axis of said shaft, a water pump carried by the hanger and driven by said shaft for supplying water to said impeller, a water pan disposed so as to supply water to said pump, and means for latching said hanger to hold said pump in operative position and when disengaged permitting the swinging of the hanger assembly upwardly to clear the pan.

ROBERT J. SEATOR.
